CONCRETE MIXER

Oscar Sheck, Milwaukee, Wis., assignor to
Koehring Company, Milwaukee, Wis., a corpora-
tion

Application March 15, 1940, Serial No. 324,196

17 Claims. (Cl. 259—163)

This invention has to do with concrete mixing machines of the type embodying plural, double, or dual drum constructions, in which concrete aggregates are first introduced into a mixing drum or chamber and partially mixed therein, thereafter transferred to a second mixing drum or chamber, wherein the mixing operation is completed, the aggregates then being finally discharged from the second chamber. More particularly, the invention relates to improvements in the control mechanism for automatically controlling the time of mixing in a mixing machine wherein the mixing of the concrete aggregates is carried on simultaneously in a plurality of mixing compartments.

In concrete mixing machines of the character referred to wherein the mixing is carried on simultaneously in a plurality of compartments, there is usually employed automatic timing control mechanism set in operation by the charging means to control after a predetermined period following the charging of the first chamber first a discharge of the aggregates in the second chamber and immediately thereafter a transfer of the partially mixed aggregates from the first to the second chamber for a final mixing action. Heretofore, in order to effect a timing control of the mixing of the aggregates transferred to the second chamber, it has been necessary to operate the charging means to reset the automatic control mechanism. However, in certain cases as where the operation of the mixing machine is being shut down, the charging means is not operated and there is no timing control of the mixing in the second chamber to which aggregates have been transferred. Since it is necessary to provide means for discharging such aggregates, there has existed the possibility of discharging such aggregates without having been mixed for the proper prescribed period of time.

It is desirable, in machines of this type, that manual operation of the concrete aggregate transferring and discharging mechanism be eliminated entirely since manual operation usually involves a time lag which cuts down the possible production of the machine. However, in the provision of automatic control mechanism it is desirable to provide manual means for interrupting the automatic control and for effecting a manual operation of the discharge means. In the case where it is not desired to immediately discharge all of the contents of the second chamber, it is desirable to return the discharge means to non-discharging position and to then effect a second discharge of the aggregates remaining

therein. Heretofore, the automatic control mechanism which provided for manual control of the transfer and discharge means has not been operative at all times to absolutely control the time of mixing of aggregates in the plural mixing chambers. This was particularly true with respect to the aggregates transferred to the second mixing drum for a final mixing operation since the timing control of the mixing of such aggregates was dependent upon the operation of the charging means to charge another batch of aggregates into the first mixing chamber.

Accordingly, one of the principal objects of this invention is to provide automatic control mechanism for a mixing machine having a plurality of mixing compartments which will be effective to assure mixing for a prescribed period in each of the compartments and prevent discharge of the concrete aggregates from the mixing compartments prior to the prescribed period of time of mixing.

A further object is to provide batchmeter control mechanism which will be effective to prevent discharge from the final mixing chamber under any condition prior to the expiration of the prescribed period of mixing time therein.

A further object is to provide automatic batchmeter control mechanism which will be operative to automatically effect a second automatic timing control of the mechanism employed for effecting a discharge of the contents of the final mixing compartment without the necessity of resetting the batchmeter to time the period of mixing in the final mixing compartment.

A further object is to provide control instrumentalities operable to interrupt the automatic control action of the batchmeter after the same has operated to start an automatic discharge of the contents of the final mixing compartment and permit manual operation of the discharge mechanism to non-discharging position and return to discharging position so as to permit splitting of the batches which have been mixed for a prescribed period of time.

Other objects and advantages of the invention will become apparent during the course of the following description.

In the drawings, there is shown a preferred embodiment of the invention. In this showing:

Figure 1 is a substantially vertical sectional view of a concrete mixing machine or paver having a pair of separate mixing compartments and showing the arrangement of the charging, transferring, and discharging mechanism, together with the control devices therefor.

Figure 2 is a front elevational view of a batchmeter, parts of the casing thereof being omitted to show the control instrumentalities by which the various operations of the mixing machine are carried out.

Figure 3 is a side elevational view of the mechanism shown in Figure 2, part of the control instrumentalities being shown in dotted lines.

Figure 4 is an enlarged diagrammatic detail side elevational view of parts of the control mechanism shown in dotted lines in Figure 3.

Figure 5 is a top plan view of the manual control levers; and

Figure 6 is a vertical sectional view taken on the line 6-6 of Figure 2 and looking in the direction of the arrows.

Referring to Figure 1 of the drawings, the numeral 1 indicates a mixing machine having separate mixing compartments 2 and 3 separated by a partition 4 having an opening 5 therein through which concrete aggregates may be transferred from the compartment 2 to the compartment 3. The compartment 2 is provided with a charging opening 6 through which concrete aggregates may be charged by a skip 7 into the compartment 2. Upon operation of the skip 7 to charge the compartment 2 with concrete aggregates, a roller 8 on the skip 7 is adapted to contact levers 9 to operate water control devices (not shown) for admitting water into the compartment 2 in a manner well known in the art.

A transfer chute 10 is provided for transferring partially mixed concrete aggregates from the compartment 2 to the compartment 3. A discharge chute 11 is provided for discharging the completely mixed aggregates from the final mixing compartment 3 through the discharge opening 12. A fluid power or hydraulic motor 13 is provided for moving the transfer chute 10 back and forth between its non-transferring position shown in solid lines to its transferring position shown in dotted lines. Likewise, a fluid power or hydraulic motor 14 is provided for moving the discharge chute 11 back and forth between its discharging position shown in solid lines and its non-discharging position shown in dotted lines. The construction of the transfer chute 10 is preferably of the type shown and described in Letters Patent No. 2,167,243 issued to E. H. Lichtenberg and Oscar Scheck.

The motor 13 is connected by conduits 15 to a transfer control valve 16 which is operable to control the action of the motor 13 to effect the desired operation of the transfer chute 10. The motor 14 is likewise connected by the conduits 17 to a discharge control valve 18 which is operable to control the action of the motor 14 to effect the desired movement of the discharged chute 11. An auxiliary motor 19 is associated with the control valve 18 and is connected by a conduit 20 to one of the conduits 15 so that upon operation of the transfer control valve 16 to admit fluid pressure to the motor 13 to effect movement of the transfer chute to transferring position, fluid pressure will also be admitted to the auxiliary motor 19 to operate the discharge control valve 18 to effect a return of the discharge valve 18 and to effect a return of the discharge chute 11 to nondischarging position.

The construction of the parts thus far described are well known in the art and form no part per se of this invention, such parts being more fully set forth and described in my copending application, Serial No. 212,834, filed June 9th, 1938, now Patent No. 2,224,801, issued

December 10, 1940. It will be understood that the novel features of this invention lie mainly in the improved control features of the batchmeter indicated as a whole by the numeral 21 which is connected by an operating member 22 to the discharge control valve 18 and by an operating member 23 to the transfer control valve 16. As is the case in my copending application, the batchmeter 21 is adapted to be reset by the rod 24 which is actuated upon the movement of the charging skip 7 to its charging position.

The construction of the parts of the batchmeter indicated by the numeral 21 in Figure 1 is shown in Figure 2 and it will be understood that the construction and operation of certain of these parts is generally similar to the batchmeter construction illustrated in Patent No. 1,451,483 issued to H. O. Winkler and to the batchmeter construction disclosed in my aforementioned application. The aforementioned Winkler patent is relied on for a more detailed showing of these parts, and for the purpose of this description, it will be sufficient to set forth that the batchmeter resetting rod 24 is connected to the batchmeter resetting arm 25 by a connecting member 26, the member 26 being a crank mounted on a shaft carrying the resetting arm 25. Operation of the rod 24 by the skip 7 will impart a counterclockwise movement to the resetting arm 25 which will impart an upward movement to a weight 26. Downward movement of the weight 26 and certain actuating devices to be described is limited by an escapement timing mechanism 27. Operation of the resetting arm 25 is resisted by a spring 28, and a counter device 29 has a connection with the resetting arm 25 to keep track of the number of times the skip is operated to reset the batchmeter.

The discharge valve 18 and its operating member 22 are connected to an actuating arm 30 which is in turn connected to the discharge control 31 by a shaft 32 to which both the operating arm 30 and control member 31 are keyed. The control member 31 is locked in the position shown in Figure 2 by means of a pivoted trip lever 33 and is moved to such position against the influence of a spring 34. It will be understood that with the parts in the position shown in Figure 2, the discharge control member 31 will maintain the discharge control valve 18 and discharge chute 11 in non-discharging position.

The transfer control valve and its operating member 23 are connected to a control member 35 which is held in the position shown in Figure 2 against the action of a spring 36 by means of a pivoted locking device 37, the locking device 37 having a detent 38 for engagement with a lug 39 on the transfer control member 35. The control member 35 is moved to the position shown in Figure 2 against the action of the spring 36 and in such position, it will be understood that the transfer control valve 16 will maintain the transfer chute 10 in its non-transferring position.

The pivotally mounted trip member 40 is connected by a rod 41 to the locking member 37, the trip lever 40 being biased by a spring 41' to a position maintaining the detent 38 in engagement with the control member 35. A transfer resetting member 42 is connected to the resetting arm 25 and is provided with a pin and slot connection 43 to the transfer control member 35 for moving the member 35 to its down position shown in Figure 2 and for returning the transfer chute to non-transferring position upon operation of the skip 7 to reset the batchmeter. The pin 43a

of the connection 43 is mounted on a lug 35a rigidly secured to the member 35. A resetting arm 44 is likewise provided with a pin and slot connection 45 to the discharge control member 31 for moving such member to the position shown in Figure 2 against the action of the spring 34 for effecting a movement of the control valve 18 and discharge chute 11 to non-discharging position upon operation of the skip 7 to reset the batchmeter.

Operating control devices are connected to the weight 26 by suitable connections for downward movement therewith and reference is now made to Figures 4 and 6 for a detail showing of the control devices indicated as a whole by the numeral 46. The control devices include a pivoted actuating member 47 adapted to engage the trip member 33 for releasing the discharge control member 31 to permit actuation of the discharge valve 18 by the spring 34 to effect movement of the discharge chute 11 to discharging position. The member 46 is also provided with an adjustable actuating member 48 adapted to contact trip lever 40 to release the transfer control member 35 and effect an actuation of the transfer valve 16 for effecting the movement of the transfer chute 10 to transferring position. Practically simultaneously with the operation of the trip member 40 by the actuating member 48 an abutment 49 will contact the pivoted actuating member 47 to move the same out of engagement with the trip member 33.

It will be recalled that upon operation of the transfer control valve 16 to move the transfer chute 10 to transferring position, fluid power will be admitted to the auxiliary motor 19 associated with the control valve 18. Admission of fluid power to the motor 19 will cause the same to actuate valve 18 and the power means 14 controlled thereby to effect a return of the discharge chute to non-discharging position, this actuation of the valve 18 being accomplished in a manner well known in the art. Such actuation of the control valve 18 will impart a downward movement to the rod 22, actuating member 30, and return the discharge control member 31 to the position shown in Figure 2 against the action of the spring 34. Upon release of the discharge trip member 33 from engagement with its actuating member 47, the trip member 33 will be returned by its spring 50 to lock the discharge control member 31 in a position preventing movement of the discharge chute 11 to discharging position.

In the normal operation of the mixing machine, the operator will cause the skip 7 to raise and charge a new batch of materials into the mixing machine upon movement of the transfer chute 10 to transfer concrete aggregates from the compartment 2 to the mixing compartment 3. Such action will also reset the batchmeter to permit operation of the trip member 33 again by its actuating member 47. However, in certain cases as where the mixing machine is being shut down for the day, or the skip is not ready for a new batch of materials, it will be apparent that a second automatic timing control of the aggregates transferred to the second chamber 3 should be provided before finally emptying the drum 3. To this end, the device 46 is provided with a second adjustable discharge operating member 51 which will contact the trip member 33 and effect a second automatic releasing action thereof to permit final discharge of the contents of the compartment 3 after the prescribed period of mixing in 75

such compartment and without the necessity of resetting the batchmeter by the loading skip 7.

With respect to the mechanism now described, it will be noted that the discharge chute 11 is automatically returned to its non-discharging position immediately upon movement of the transfer chute 10 to transferring position, and will be locked in such position by the trip member 33 and control member 31. It will, therefore, be apparent that the automatic actuating control mechanism is effective to prevent operation of the discharge chute 11 to discharge aggregates from the final mixing chamber 3 prior to the expiration of the prescribed period of mixing therein.

15. In order that the operator will know that the discharge control member 31 has operated to effect a discharge action of the discharge chute 11, signal light 52 is provided and has one of its lead wires connected to a switch member 53 engageable with a contact member 54 mounted on the discharge control member 31. Upon release of the discharge control member 31, the pin 54 will move into engagement with the contact member 53 and complete the circuit for operating the discharge signal light 52.

30. Likewise, a signal light 53' is provided for advising the operator that it is time to start the mechanism to control the action of the skip 7 to charge the machine with a new batch of materials. The signal light 53' has one of its leads connected to a switch member 54' and a pin 55 is mounted on the control actuating device 46 for the engagement with the switch member 54'. The switch member 54' is pivotally mounted and 35 spring based towards a predetermined position as determined by the adjustable abutment member 56 which is movable into engagement with the side of the casing of the batchmeter. The switch member 54' is pivotally mounted so as to be movable downwardly with the pin 55 and actuating device 46 without interfering with the circuit completed through the signal light 53', a sliding action of the pin 55 taking place on the switch member 54'. The adjustment of the member 45. 40. 45. 50. 55. 60. 65. 70. 75. 80. 85. 90. 95. 100. 105. 110. 115. 120. 125. 130. 135. 140. 145. 150. 155. 160. 165. 170. 175. 180. 185. 190. 195. 200. 205. 210. 215. The member 57 is pivotally connected to a link 59 which in turn is connected to a member 60 pivotally secured to the casing of the batchmeter. The member 60 carries an abutment 61 and upon movement of the member 57 to its upper position with the abutment 58 in engagement with the edge of the casing surrounding the opening through which the member 57 extends, the abutment 61 which will be moved to a position adapted to contact the trip member 33 just after actuation thereof by the member 47 and prior to actuation of the trip member 40 to effect a transfer action. Such engagement will prevent further downward action of the member 46, by reason of further downward movement of the member 47 being prevented by its engagement with the trip member 33.

As in my aforementioned accompanying application, manually operable handles 62 and 63 are provided for interrupting the automatic operation of the mixing machine. The handle 62 is associated with the discharge control valve 18 and the handle 63 is associated with the transfer control valve 16. As is best shown in Figure 3, the manually operable handles are connected to their respective control valves by toggle links 64 and 65 which are pivotally connected together by pins 66, the pins 66 riding in slots 67 formed in the control handles and as shown in connection with the discharge control handle 62. The control handles are also provided with notches 68 for engagement with a locking member 69.

Accordingly, it will be apparent that by pulling the handles outwardly and placing the notch 68 in engagement with the locking member 69, operation of the control valves by the batchmeter will be prevented. For example, if the control handle 62 is pulled outwardly and its notch 68 placed in engagement with the locking member 69, the ends 70 of the slot 67 will engage with the pin 66 to prevent downward movement of the pin 71 connecting the link 65 to the operating member 72 for the discharge control valve 18 and thereby preventing upward movement of the discharge operating member 22 under the influence of the batchmeter.

Although the operation of the handles 62 and 63 in preventing automatic operation of the control valves 16 and 18 is the same as in my aforementioned application, these handles cooperate with the manual interrupting handle 57 in a new manner to be described. Upon operation of the manual control 57 to position the abutment 61 so as to interrupt the automatic control operation of the batchmeter 21, the batchmeter will operate the trip lever 33 through the operating member 47 to effect a discharge operation of the discharge chute 11. As soon as this action takes place, the trip lever 33 will contact the abutment 61 and further downward movement of the operating device 46 in the batchmeter 21 will be prevented. The operator of the mixing machine may then return the discharge chute 11 to mixing position prior to a complete discharge of the contents of the mixing chamber 3 by pulling outwardly on the handle 62 to operate the control valve 18 for returning the chute 11 to its mixing position. In this way, it is possible for the operator to split batches and only discharge the amount of completely mixed concrete which is needed from the final mixing chamber 3. To restore the automatic operation under the control of the batchmeter after such interrupted operation, it is merely necessary to move

the handle 57 to lower the abutment 61 so as to permit continued downward movement of the operating member 46 to effect a transfer action of the transfer chute 10 through the operating member 48.

The operation of the apparatus is as follows: Assuming that batches of concrete are being mixed in both of the mixing chambers 2 and 3, the batchmeter 21 will first operate to trip the locking lever 33 to effect an action of the discharge control valve 18 to move the discharge chute 11 to discharging position to discharge the completely mixed batch of concrete from the mixing chamber 3. Thereafter, after further downward movement of the weight 26 the batchmeter through member 48 will trip the lever 40 to effect an action of the transfer valve 16 to turn the transfer chute 10 to transferring position for transferring the batch of concrete in the mixing chamber 2 to the mixing chamber 3 through the opening 5. When the valve 16 is thus operated to move the transfer chute to transferring position, fluid pressure will be admitted to the air cylinder 19 to return the valve 18 and the discharge chute 11 to non-discharging position. As this action takes place, the pivotally movable operating member 47 will contact the abutment 49 and release the trip lever 33 for movement under the influence of its spring 30 50 to locking position for locking the discharging control member 31 to prevent movement of the discharge chute 11 from non-discharging position. After such locking action of the trip lever 33, it will be noted that it is impossible to effect an operation of the discharge chute 11 except after a predetermined timing control of the batchmeter 21.

In the normal operation of the apparatus, the pin 55 will contact the switch 54' shortly after the transfer chute 10 is moved to transferring position to cause the light 53' to go into operation and to advise the operator to start the skip 7 upwardly with a new batch of unmixed aggregates for the chamber 2. As the skip 7 goes up to charge the mixing chamber 2 with a new batch of materials, it will operate the rod 24 to reset the batchmeter through the resetting member 25. As the resetting member 25 is moved counterclockwise, the link 42 will impart a downward movement to the transfer control member 35 to return the valve 16 and transfer chute 10 to non-transferring position. In the event that the discharge chute is in discharging position, the link 44 will operate the member 31 to return the discharge valve 18 and the discharge chute 11 to non-discharging position. Thereafter, the batchmeter will continue its cycle as before stated with the initial operation being the tripping of the lever 33 to effect a discharge action of the discharge chute.

It will be recalled that upon movement of the transfer chute 10 to transferring position, the discharge chute 11 is returned to non-discharging position and locked in such position. If the skip 7 is not raised with a new batch of unmixed concrete aggregates for the first mixing chamber 2, then the operating member 51 will effect a second action of the trip member 33 to release the discharge control valve 18 for actuation.

This action will take place in those cases where it is desired to shut down the operation of the mixing machine at the end of the day for where the skip 7 has not been loaded with a batch of unmixed aggregates and it is desired to discharge

the concrete from the chamber 3 without raising the skip 7. It will be noted that upon release of the trip lever 33 by the operating member 51, the discharge control valve 18 will not be operated since the transfer chute 10 will be in transferring position and the control valve 18 will be held in non-discharging position by the motor 19. Accordingly, to effect a discharge of the mixing chamber 3 after release of the trip lever 33 by the member 51, it will be necessary to first operate the handle 63 to return the transfer chute 10 to non-transferring position thereby releasing the fluid pressure from the motor 19 and thus permitting operation of the discharge valve 18. The handle 62 may then be operated to effect a movement of the discharge control valve 18 to discharging position for effecting a movement of the discharge chute 11 to its discharging position.

From the foregoing, it will be apparent that there is provided a batchmeter construction which will be effective to automatically control the time of mixing in the chambers 2 and 3 and for effecting the discharge of completely mixed concrete from the chamber 3 and for effecting the transfer of partially mixed concrete from the chamber 2 into the chamber 3. Moreover, there is provided means for interrupting the automatic operation of the batchmeter to take care of certain operating conditions without interfering with the timing control action of the batchmeter in preventing the transfer or discharge action from taking place prior to the completion of the mixing in either the chamber 2 or 3.

It will also be apparent that the provision of the pivoted operating member 47 and cooperating abutment 49 provides for an automatic locking of the discharge means in non-discharging position after operation of the transfer means to transfer material from the compartment 2 to the compartment 3. It is thereafter impossible to effect a discharge of the compartment 3 without a timing control action of the batchmeter 21. This timing control is provided by the operating member 51 which will effect a second automatic release action of the trip lever 33 in those cases where the skip 7 is not operated to reset the batchmeter 21 after operation of the transfer means.

Accordingly, it will be apparent that the batchmeter 21 will be effective to cause a discharge action of the chamber 3. The batchmeter 21 will also thereafter time the mixing period in the chamber 2 and then effect the transfer of the partially mixed aggregates to the chamber 3 for a further control period. At the end of such period, it will operate to release the discharge means to permit the discharge from the compartment 3. In this manner, the batchmeter 21 is operative on a single setting thereof to time and control movements of a batch of aggregates from the time it is charged through the opening 6 into the compartment 2 until it is completely mixed and ready for discharge from the chamber 3 through the opening 12.

Having thus described my invention, what I claim as new and desire to secure by Letters Patent of the United States, is:

1. In combination, a mixer having a plurality of mixing chambers, discharge means for said mixer movable to discharging and non-discharging positions, transfer means intermediate said mixing chambers and movable to transferring and non-transferring positions, and a batch- 70 meter unit controlling the time of mixing in said chambers including instrumentalities for operating said transfer and discharge means to effect a return and lock of said discharge means in non-discharging position upon movement of said transfer means to transferring position.

2. In a mixing machine of the class described, a mixer comprising a plurality of mixing chambers, one arranged to receive aggregates from the other, a transfer means for transferring aggregates from one of the mixing chambers to the other and movable to transferring and non-transferring positions, a discharge means for discharging the aggregates transferred to said other mixing chamber and movable to discharging and non-discharging positions, and a batchmeter unit controlling the time of mixing in said chambers including instrumentalities for operating said transfer and discharge means to effect a return and locking action of said discharge means in non-discharging position upon movement of said transfer means to transferring position, said batchmeter being operable to prevent operation of said discharge means to discharging position 25 after its return to non-discharging position until it has operated to control the time of mixing in said other mixing chamber.

3. In a mixing machine of the class described, a mixer comprising a plurality of mixing chambers, one arranged to receive aggregates from the other, a transfer means for transferring aggregates from one of the mixing chambers to the other and movable to transferring and non-transferring positions, a discharge means for discharging the aggregates transferred to said other mixing chamber and movable to discharging and non-discharging positions, separate operating instrumentalities for said transfer and discharge means, a batchmeter having a first control device for actuating one of said operating instrumentalities to effect a movement of said discharge means to discharging position, a second control device for subsequently actuating the other of said control instrumentalities to effect a movement of said transfer means to transferring position, and including mechanism for returning and locking said discharge means and the operating instrumentality therefor in non-discharging position upon operation of said transfer means by said second control device for a subsequent operation by said first control device.

4. In a mixing machine of the class described, a mixer comprising a plurality of mixing chambers, one arranged to receive aggregates from the other, a transfer means for transferring aggregates from one of the mixer chambers to the other and movable to transferring and non-transferring positions, a discharge means for discharging the aggregates transferred to said other mixing chamber and movable to discharging and non-discharging positions, separate operating instrumentalities for said transfer and discharge means, a batchmeter having a first control device for actuating one of said operating instrumentalities to effect a movement of said discharge means to discharging position, a second control device for subsequently actuating the other of said control instrumentalities to effect a movement of said transfer means to transferring position, including mechanism for returning and locking said discharge means and the operating instrumentality therefor in non-discharging position upon operation of said transfer means by said second control device, and a third con-

trol device for effecting a second timed automatic operation of said first operating instrumentality for said discharge means.

5. In a mixing machine of the class described, a mixer having a plurality of mixing chambers, one arranged to receive aggregates from the other, charging means to introduce aggregates into one of said chambers, transfer means to carry said aggregates from said one chamber to a second chamber and movable to transferring and non-transferring positions, discharge means for the second chamber movable to discharging and non-discharging positions, and a batchmeter unit controlling the time of mixing of aggregates in said chambers and normally operative to effect an action of the discharge means to discharge aggregates from said second chamber and thereafter an action of the transfer means to transfer the aggregates from said one to said second chamber for a timed mixing therein, and means operative directly from the charging means upon operation thereof to reset said batchmeter after said transfer action, said batchmeter including instrumentalities for effecting a second timed control of the discharge means without operation of the charging means to reset the batchmeter to effect a second timing control period of the aggregates transferred to said second chamber.

6. In a mixing machine of the class described, a mixer having a plurality of mixing chambers, one arranged to receive aggregates from the other, charging means to introduce aggregates into one of said chambers, transfer means to carry said aggregates from said one chamber to a second chamber and movable to transferring and non-transferring positions, discharge means for the second chamber movable to discharging and non-discharging positions, separate operating instrumentalities for said transfer and discharge means, a batchmeter having separate control devices for each of said operating instrumentalities, means operative from the charging means upon operation thereof to charge said first chamber with a batch of unmixed aggregates for setting the batchmeter into operation, said batchmeter being operative after a predetermined time to actuate one of said control devices and its associated control instrumentality to effect an operation of said transfer means to transfer said batch of aggregates to said second chamber for an additional mixing period, said batchmeter being further operative to control the time of mixing in said second chamber and at the end of such time to actuate the other of said control devices and its associated operating instrumentality to permit the discharge of said batch of aggregates from said second chamber without a second operation of the charging means.

7. In a mixing machine of the class described, a mixer having a plurality of mixing chambers, one arranged to receive aggregates from the other, charging means to introduce aggregates into one of said chambers, transfer means to carry said aggregates from said one chamber to a second chamber and movable to transferring and non-transferring positions, discharge means for the second chamber movable to discharging and non-discharging positions, and a batchmeter unit operative from the charging means upon operation thereof to charge a batch of unmixed aggregates into the first of said chambers for controlling the time of mixing in said chambers and to cause timed sequential operation of the

transfer and discharge means to transfer the batch of aggregates after partial mixing from said first to said second chamber and after further mixing in said second chamber to control 5 an operation of said discharge means to permit the discharge of said batch of aggregates from said mixer.

8. In a mixing machine of the class described, a mixer having a plurality of mixing chambers, one arranged to receive aggregates from the other, charging means to introduce aggregates into one of said chambers, transfer means to carry said aggregates from said one chamber to a second chamber and movable to transferring and non-transferring positions, discharge means for the second chamber movable to discharging and non-discharging positions, separate operating instrumentalities for said transfer and discharge means, a batchmeter controlling the sequential 15 operation of said operating instrumentalities and thereby the time of mixing in said chambers, resetting means operative directly from the charging means, said batchmeter having a resetting lever operable by said resetting means, and connections between each of said operating instrumentalities and said resetting lever for resetting said operating instrumentalities for subsequent control operation by said batchmeter upon operation of said resetting lever.

9. In a mixing machine of the class described, a mixer having a plurality of mixing chambers, one arranged to receive aggregates from the other, charging means to introduce aggregates into one of said chambers, transfer means to carry said aggregates from said one chamber to a second chamber and movable to transferring and non-transferring positions, discharge means for the second chamber movable to discharging and non-discharging positions, separate operating instrumentalities for said transfer and discharge means, a batchmeter controlling the sequential operation of said operating instrumentalities and operative to effect actuation of one of said operating instrumentalities to effect a transfer action after operation of the other of said instrumentalities to effect a discharge action, resetting means operative directly from the charging means, said batchmeter having a resetting lever operable by said resetting means, and a connection between said one operating instrumentality for said transfer means and said resetting lever for resetting said one operating instrumentality and thereby effecting a return of said transfer means upon operation of said charging means.

10. In a mixing machine of the class described, a mixer having a plurality of mixing chambers, one arranged to receive aggregates from the other, charging means to introduce aggregates into one of said chambers, transfer means to carry said aggregates from said one chamber to a second chamber and movable to transferring and non-transferring positions, discharge means for the second chamber movable to discharging and non-discharging positions, a batchmeter operable from said charging means for controlling sequentially first the operation of said discharge means and second the operation of said transfer means, and a signal means operable by said batchmeter after operation of said transfer means to effect a transfer action to advise the operator to start operation of the charging means, said signal including adjustable means for permitting its operation by said batchmeter at a variable interval of time after operation of said transfer means so as to adjustably control the interval of

time between operation of said transfer means and operation of said charging means.

11. In a mixing machine of the class described, a mixer having a plurality of mixing chambers, one arranged to receive aggregates from the other, charging means to introduce aggregates into one of said chambers, transfer means to carry said aggregates from said one chamber to a second chamber and movable to transferring and non-transferring positions, discharge means for the second chamber movable to discharging and non-discharging positions, a batchmeter operable from said charging means and including mechanism for automatically controlling sequentially first the operation of said discharge means and second the operation of said transfer means, and a manually operable device engageable with the batchmeter mechanism for interrupting the automatic action thereof after operation of said discharge means to effect a discharge action, and manual means for returning said discharge means to non-discharging position to permit partial discharge of the contents of the second chamber at different times, said manually operable device being disengageable from said batchmeter mechanism to reestablish automatic control thereby for thereafter effecting a timed automatic control action of said transfer means.

12. In a mixing machine of the class described, a mixer comprising a plurality of mixing chambers, one arranged to receive aggregates from the other, a transfer means for transferring aggregates from one of the mixing chambers to the other and movable to transferring and non-transferring positions, a discharge means for discharging the aggregates transferred to said other mixing chamber and movable to discharging and non-discharging positions, a batchmeter having a locking trip lever for controlling the action of said discharge means and a second trip lever for controlling the action of said transfer means, an operating device for actuating said first trip lever to effect a discharge action of said discharge means, a second operating device for actuating said second trip lever to effect a transfer action of said transfer means, means operable upon actuation of said second trip lever for returning said discharge means and said first locking trip lever to non-discharging position, and a third operating device for effecting a timed automatic second operation of said first trip lever to effect a second discharge action of said discharge means.

13. Apparatus as claimed in claim 12, wherein said first locking trip lever has a bias to locking position and said first operating device is movable out of engagement therewith, together with means for effecting movement of said first operating device out of engagement with said first trip lever substantially upon operation of said second trip lever to permit the return of said first trip lever to locking position under its bias for a second timed automatic action by said third operating device.

14. In a mixing machine, plural mixing

chambers, charging means for a first chamber, discharge means for the second chamber, transfer means to transfer aggregates from the first to the second chambers, automatic control mechanism including controlling devices for the said transfer and discharge means, operation initiating devices between said automatic control mechanism and the charging means for setting into operation the automatic control mechanism upon operation of the charging means to operate in timed relation, first the discharge control device, next the transfer control device, and then again the discharge control device.

15. In a mixing machine, plural mixing chambers, charging means for a first chamber, discharge means for the second chamber, transfer means to transfer aggregates from the first to the second chambers, automatic control mechanism including controlling devices for the said transfer and discharge means, operation initiating devices between said automatic control mechanism and the charging means for setting into operation the automatic control mechanism upon operation of the charging means to operate in timed relation, first the discharge control device, next the transfer control device, and then again the discharge control device, said automatic control mechanism including connections to the charging means which when the charging means is actuated to charge the first chamber prior to the second actuation of the discharge control device will prevent such second action by the automatic control mechanism.

16. In a mixing machine, plural mixing chambers, charging means for a first chamber, discharge means for the second chamber, transfer means to transfer aggregates from the first to the second chambers, automatic control mechanism including controlling devices for the said transfer and discharge means, and connections between the charging means and the automatic control mechanism to initiate the operation of the latter, the automatic control mechanism comprising instrumentalities to operate the discharge control device twice and the transfer control device once in a single action of the automatic mechanism.

17. In a mixing machine, plural mixing chambers, charging means for a first chamber, discharge means for the second chamber, transfer means to transfer aggregates from the first to the second chambers, actuating devices for the transfer and discharge means, and automatic operating devices controlled from the charging action of the charging means to in turn operate the discharge actuating device, then the transfer actuating device, and then the discharge actuating device a second time, including interference mechanism operable when the charging means is actuated to charge a second time prior to operation of the discharge operating device a second time for preventing the actuation of said discharge actuating device a second time as aforesaid.

OSCAR SHECK.
